PUMP

Robert H. McBean, Fairview Village, Ohio, assignor to The Deming Company, Salem, Ohio, a corporation of Ohio

Application August 1, 1945, Serial No. 608,114

7 Claims. (Cl. 103—5)

1

This invention relates to a pumping mechanism of the jet type wherein there is a pressure pump and a jet to aid in the delivery of liquid thereto, the jet being energized by liquid under pressure delivered thereto by the pressure pump. In the case of a shallow well pump the jet is located within the pump casing itself. In the case of a deep well pump it is located in the well and supplied by a suitable conduit leading downwardly from the pump above ground.

The primary object of the invention is to provide simple and effective means for readily converting these pumps from the shall well type to the deep well type. More particularly, it is an object of the invention to provide jet mechanism for the shallow well pump interchangeable with means to supply a pressure jet in the well, each of such interchangeable devices being adapted to be mounted in the pump casing.

It is a further object to provide each of said interchangeable devices with means for attaching the suction pipe thereto in communication with a suitable internal conduit which may carry the liquid for the pump, each of said devices having also another conduit adapted to conduct liquid under pressure for operating the corresponding jet.

It is a still further object of the invention to provide a jet nozzle, a jet tube, and means providing a passageway to the nozzle, all mounted as a unit in the base of the pump casing beneath the pressure pump and adapted to be withdrawn as a unit therefrom and replaced by means mounted in the same opening to connect the same pressure chamber in the pump with a pressure conduit adapted to lead to a jet located in the well when the conversion is to be made to the deep well type of pump.

My invention is hereinafter more fully described in connection with a preferred embodiment thereof illustrated in the drawings, the essential novel features being summarized in the claims.

In the drawings, Fig. 1 is an elevation partly in section and partly broken away of my pump arranged for shallow well operation and associated with a pressure tank and suitable controlling devices to constitute a water system; Fig. 2 is a sectional side elevation of the shallow well pump; Fig. 3 is a sectional elevation, partly broken away, of my pump equipped for operation as a deep well pump in a water system, the pressure tank and the controls shown in Fig. 1 being applicable to this figure but omitted for simplicity; Fig. 4 is a vertical section of the lower portion of my pump equipped for deep well operation; Fig. 5 is a fragmentary vertical section in the same plane as Fig. 4 of the lower portion of the pump casing without the conducting devices for either shallow well or deep well; Fig. 6

2

is a section of a device popularly known as a "Brady Air Control" for supplying air to the pressure tank and maintaining it at a definite pressure, the control being shown connected as in Fig. 1; Fig. 7 is a horizontal section through the lower portion of the pump when equipped as a shallow well pump, this view being in section on the plane indicated by the line 1—7 in Fig. 2; Fig. 8 is a similar view showing the pump equipped for a deep well operation, this view being in section on the plane indicated by the line 8—8 on Fig. 4; Fig. 9 is a detail in vertical section through the conduit to the shallow well jet nozzle, the plane of the section being indicated by the line 9—9 on Figs. 2 and 7; Figs. 10 and 11 are details in section of the deep well installation, the planes of the sections being indicated by the correspondingly numbered lines on Figs. 4 and 8.

Briefly, in Fig. 1, 10 indicates the casing or bare portion of my pump carrying a suitable pressure pump as hereinafter described and having above it a casing 11 housing a driving motor, not shown. The casing 11 is supported by an open frame 13 which rests on top of the casing 10 and allows access to a coupling between the motor and pump. Leading outwardly and downwardly from the base portion of the pump is a suction pipe 20, shown as terminating in a strainer and check unit 21 in a suitable source of liquid supply. Extending from the top region of the casing 10 is a delivery pipe 30 which leads to a pressure tank 40 which is the service tank of a water system. 50 indicates a pressure operated electric switch for controlling the motor and 60 the Brady air control, which in effect is a local automatic pump operated by the force in the suction pipe through a connecting pipe 61 and serving to force air into the pressure tank as needed to maintain a predetermined pressure therein.

The above description of the external parts applies also to the deep well installation of Fig. 3, except that the suction pipe 20a is connected at 45 its lower end to a jet housing 23 the lower end of which is in communication with the strainer and check valve unit 21. In the jet housing 23 is an upwardly facing nozzle 24 discharging into a flaring jet tube 25, communicating with the lower end of the suction pipe 20a. The jet nozzle is supplied by liquid under pressure through a drive pipe 28 in communication with the pump, and leading downwardly to an elbow passage in the jet housing terminating in the nozzle 24.

The constructions so far described and illustrated as Figs. 1 and 3 are common to these types of pumps for shallow well and deep well use respectively. My invention is concerned with the jet arrangements within the pump casing 10 in Fig. 1 and with the means for supplying connec-

tions from the casing to the suction 20a and the drive pipe 28 in Fig. 3, all of which will be apparent from the following description.

Referring now to Fig. 2, it will be understood that the motor in the upper casing 11 has a vertical shaft 70, the lower end of which is connected by a coupling 71 to a shaft 72 of the pressure pump. As shown, this pump comprises a centrifugal impeller 74 in a suitable volute casing 76, 77. The edge of the impeller 78 is on its underside at the center, and the liquid there received is discharged outwardly and upwardly into an annular chamber A in the casing 10.

The impeller 74 is shown as having a bearing in a sleeve 79 carried by a transverse partition 16 in the pump casing member 10. Surrounding the sleeve 79 is the lower portion 77 of the impeller housing. The upper member 76 of this housing is shown as an integral part of the frame member 13 and carried by a bottom portion 17 thereof, which has a tubular portion 18 extending downwardly to the housing portion 76. The tubular portion is shown as carrying a suitable internal bearing for the shaft 72.

The internal pump construction described is intended to be illustrative of any rotary or centrifugal pump on a vertical shaft receiving its supply from a downwardly open eye 78 and discharging into an internal stilling chamber A within the casing, the stilling chamber being above the pump. From the top portion of the stilling chamber a suitable orifice indicated by the dotted circle 31 in Fig. 2 leads to the discharge pipe 30.

The bottom 12 of the casing and the partition 16 are connected by arcuate walls to form horizontal cylindrical barrel 80 which is closed at the outer end as shown at 81 and open at the inner end 82 when neither the shallow well jet nor the connection to the deep well jet is mounted in the casing. This demounted condition is shown in Fig. 5, at which time the open end of the barrel 80 is in communication with a base chamber B which is in open communication with the stilling chamber A. The barrel 80 communicates intermediately with the eye 78 of the impeller and is equally applicable to shallow well and deep well constructions.

I will now describe the jet unit which coacts with the casing member 10 and with the barrel 80 to convey liquid from the suction pipe 20 to the eye of the impeller and boost the flow by a jet receiving its force by liquid under pressure from the stilling chamber imparted by the pump. This shallow well jet unit is best shown in Figs. 2, 7 and 9. As shown in these figures the jet unit comprises three parts, namely, the hollow thimble 90, the jet nozzle 100, and the jet tube 110 into which the nozzle discharges.

The thimble 90 is a cup-like member having external flange 94 by which it is secured to the casing. The flange overhangs an annular seat on the casing and, as shown, cap screws 95 pass through the flange and through an interposed gasket 96 into threaded recesses 97 (Fig. 5) in the casing. At its inner edge the thimble has an annular shoulder 92 bearing against the end of the barrel 80 with an interposed gasket 93. The thimble also preferably has a slight extension beyond the gasket seat closely fitting the interior of the barrel 80. In the interior of the thimble the material is formed into an integral elbow 98 which carries a passageway 99 leading from the base chamber B inwardly and then axially to the nozzle, as shown in Fig. 7.

It will be seen that when the thimble 90 is placed as shown in Fig. 2, it makes a tight connection with the casing and with the end of the barrel 80, while its elbow space 98 is in open communication with the base chamber B. The outer end portion of the thimble is internally threaded and the suction pipe 20 screws tightly into such thread as shown in Figs. 2 and 7.

10 The jet nozzle 100 which coacts with the thimble elbow 98 in a substantially water-tight manner is preferably carried by the jet tube 110. As shown the jet tube has the usual internal bore of an intermediate comparatively cylindrical portion 112, a flaring portion 113 leading thereto and a flaring portion 114 leading therefrom. The exterior of the tube is preferably threaded as shown at 115 and screws snugly into the end of the thimble. The jet tube is provided with 15 an extension 116 which carries the jet nozzle 100. This extension surrounds the nozzle but has lateral openings 117 into it opposite the side portion of the nozzle and adjacent the flaring opening 113 of the jet tube. The nozzle is preferably forced tightly into the extension and the end of the extension bears snugly against the end of the elbow 98 as shown in Fig. 7.

20 When the jet unit has been installed as shown in Figs. 2 and 7, and the pump filled with water is started, such water comes by suction up the pipe 20 and around the exterior of the jet tube extension, thence through the passageways 117 and thence through the jet tube. It thus comes against a wall carried by the casing and is diverted around the jet tube and passes into the eye 78 of the impeller. The wall of the casing is shown with an annular curved recess 119 to reduce the friction as the water returns the direction from the central jet tube bore to the 25 annular space about it. It may be convenient in manufacture to make the end wall opposite the tube removable, but in any case it is rigid in use and, hence, for simplicity is shown as integral.

30 45 Now as the suction water is delivered by the passageway described to the eye of the impeller it is forced under pressure upwardly to chamber A. Here the air naturally rises to the top of the chamber and is delivered with the discharged 50 water to the pressure tank 40 while air-free water from the lower portion of the chamber passes downwardly into the chamber B. As this water is under pump pressure some of it passes through the elbow of the thimble and thence 55 into the nozzle 100. This makes a vigorous jet passing axially into the jet tube and thus boosting the suction which also flows into the tube and thence to the impeller and stilling chamber.

60 65 The shallow well jet pump above described may be very readily converted into a deep well jet pump by the mere removal of the jet unit comprising the thimble, nozzle and tube and the substitution therefor of the connecting device shown at 120 in Figs. 4, 8, 10 and 11. This connecting device forms the means for connecting the suction pipe 20a with the suction side of the pump and the drive pipe 28 with the pressure side. It 70 comprises a barrel 120 adapted to occupy the casing passageway 85 in place of the thimble 90, this barrel having two internal passageways, one of which extends from the outer end to the inner end in communication with the casing barrel 80, the other of which extends from the outer end in-

wardly and diverges laterally in communication with the chamber B.

The barrel 120 has an externally cylindrical portion 121, the outside diameter of which is the same as the corresponding diameter of the thimble 95. It thus fits snugly in the opening 85. The inner end of the cylindrical portion having an annular seat 123 which bears against the end of the casing barrel 80 through an interposed gasket 124. The innermost portion of the barrel is preferably a small cylindrical flange extending into the interior of the barrel 80.

The barrel 120 is divided by means of an internal septum 125 which connects with one portion of the barrel wall adjacent the inner end thereof and curves inwardly and then extends in a straight direction to the outer end. This provides two passageways D and E within the barrel 120. The passageway D leads from the suction pipe 20a (which screws into a threaded opening in the outer end of the barrel) and thence continues lengthwise of the barrel to the central open inner end thereof which registers with the casing barrel 80. This provides a direct course for suction from the suction pipe 20a to the eye of the impeller. The passageway E on the other hand leads from the pressure chamber B in the base of the pump inwardly and by a gradual course outwardly to a threaded opening which receives the pressure drive pipe 28 leading to the jet in the well.

Accordingly, when the deep well construction has been installed and the pump filled with water to operate it, the pressure caused by the rotating pump in the chamber A passes to the chamber B and thence through the passageway E to the drive pipe 28, thus supplying the upwardly facing jet nozzle 24 in the deep well jet. This forces suction water upwardly in the jet to boost the suction water coming through the strainer 21 and passing upwardly around the nozzle and into the jet tube and thence into the suction pipe 20a.

A valve 130 is placed between the pump and the pressure tank. This valve is used when the pump is used as a deep well pump and serves to reduce the flow from the pump to insure sufficient flow of fluid to the jet 23 in the well. This valve may be manually adjusted and once adjusted does not need further attention. Such valve, while shown applied to the pump when used for shallow wells, may be eliminated if so desired.

In a water system it is desirable to maintain a certain air pressure within the service tank 40. This may be well effected by supplying the tank with an automatic air pumping attachment which also automatically controls the water level in the tank. For the sake of completeness, I have shown and will now describe the general characteristics and operation of such an air pump. It is indicated at 60 at Fig. 1 and is attached to the tank and connected through tubing 61 to the suction side of the pump. The suction pull of the pump moves a diaphragm of the air pump, thus drawing external air through a snifter valve into the space on the tank side of the diaphragm. When the pump stops, the pressure is equalized on both sides of the diaphragm and the trapped air is forced by a spring into the tank. This action occurs with each start and stop of the pump, until the proper amount of air has been forced into the tank, at which time the air pump automatically stops delivering air. No air passes from this device through the pump to cause a decrease in pump capacity or to break suction.

One form of automatic air pumping attach-

ment above outlined is shown in Fig. 6 where 130 indicates one member of a casing secured to the tank having its interior in communication therewith. The other member 131 of the casing is formed to leave a space between said members in which is a diaphragm 133 and a spring 134 pressing the diaphragm toward the tank. The pipe 61 from the suction conduit to the water pump communicates with the internal space occupied by the spring on that side of the diaphragm. On the other side of the diaphragm there is a passageway from the space to the snifter valve 135, which is an inwardly opening check valve under spring control and adjusted to allow the entrance of air when the diaphragm moves outwardly against its spring.

Accordingly, when the pump starts the suction pull moves the diaphragm outwardly against the pressure of the spring, then when the suction ceases the spring forces the air drawn through 20 the snifter valve into the space beyond the diaphragm into the pressure tank. There may be a 25 check valve between the diaphragm and pressure tank opening into the tank, or a similar 30 checking operation may be effected by making the passage to the tank materially smaller than that from the exterior to the diaphragm, as 35 shown in Fig. 6.

It will be seen that my pump is well adapted for 30 use in a water system having a pressure service tank and of course it is equally adapted for pumping to an open discharge or into a continuous pipe. The adaptation to shallow well or deep well installations is readily made and involves merely two simple and comparatively inexpensive 35 interchangeable units, either being attached in the same position to the pump casing through a single opening therein, and seating against the same casing surfaces.

I claim:

1. In a pumping device, a pressure pump, a casing provided with a pressure chamber in communication with the pressure side of said pump, a discharge passage leading from said chamber to the exterior of said casing, a passageway in said casing in communication with the suction side of the pump and having an open end terminating in a plane spaced from the external wall of said casing, a member removably mounted on said casing and extending into the interior of said chamber, a jet pump carried by said member and having a pressure inlet and a suction inlet and a jet tube, said jet tube discharging into said passageway, said member having two passageways one of which extends from the suction inlet of said jet pump to the exterior of said casing and the other of which extends from the pressure inlet of said jet pump to said pressure chamber.

2. In a pumping device a pressure pump, a casing providing a pressure chamber in communication with the discharge of said pump, said casing having a pair of openings each providing communication between said chamber and the exterior of said pump, a barrel in said chamber and in communication with the suction side of said pump, and having an open end spaced from the wall of said casing, a thimble secured to said casing and extending through one of said openings into said pressure chamber, the inner end of said thimble abutting the open end of said barrel, a jet pump mounted on said thimble and having a jet tube extending and discharging into said barrel, said jet pump having a pressure inlet and a suction inlet, and said thimble having one pas-

sageway extending from the pressure inlet of the jet pump to the pressure chamber and a second passageway extending from the suction inlet of the jet pump to the exterior of said casing.

3. In a pumping device, a rotary pressure pump, a casing surrounding said pump and providing a pressure chamber extending above and below the pump and in communication with the discharge thereof, means adjacent the top of said chamber providing a pressure discharge from the device, a conduit in said chamber below the rotary pump and in communication with the suction side thereof and having an open end terminating in a plane spaced from the internal wall of said casing, said casing having an opening in alignment with said conduit, a hollow member removably secured to said casing and extending through the opening therein into an abutting relation with said conduit thereby sealing said conduit from direct access to said pressure chamber, said member having a jet pump mounted thereon and including a jet tube, a pressure inlet and a suction inlet, said jet tube extending into said conduit, said member having a passageway extending from the suction inlet of the jet pump to the exterior of said casing and a second passageway extending from the pressure chamber to the pressure inlet of said jet pump.

4. A device for converting a deep well pump to a shallow well pump and comprising a pump casing, a cylindrical member adapted to extend into the pump casing, a flange on one end of said member adapted to be secured to the pump casing, a jet pump tube secured to and extending outwardly from the other end of said member, a jet mounted within said jet tube, said member having a passageway extending from the open flanged end of said member and encircling the inner end of said tube and communicating with passageways formed in the wall of said tube, said member having an integrally formed hollow elbow providing a passageway extending from said jet to an opening in the cylindrical wall of said member.

5. In a pump, the combination of a hollow base and a surmounting casing providing two connected pressure chambers, one in the casing and one in the base, an opening from the exterior into the base pressure chamber, an impeller within the casing having its suction orifice by means of a passageway through the partition wall between the base and the casing, a fixed tubular member within the hollow base communicating at one end with the suction orifice of the impeller and at the other end having an open orifice within the base pressure chamber and registering with but spaced from said opening from the exterior into the base, and a hollow member adapted to extend through the said opening in the base and engage at the inner end with the fixed tubular suction member in the base and adjacent the outer end with the wall of the base, said hollow member having a longitudinal passageway leading from the exterior to the inner end of the hollow member and having a lateral passageway leading from an orifice through the wall of the hollow member in a region within the pressure chamber in the base, said hollow member having internal passageway communicating with said wall orifice and adapted to discharge liquid under pressure from the pressure chamber in the base.

6. In a pump, the combination of a hollow base and a surmounting casing providing two

connected pressure chambers, one in the casing and one in the base, an opening from the exterior into the base pressure chamber, an impeller within the casing having its suction orifice by means of a passageway through the partition wall between the base and the casing, a fixed tubular member within the hollow base communicating at one end with the suction orifice of the impeller and at the other end having an open orifice within the base pressure chamber and registering with but spaced from said opening from the exterior into the base, and a hollow member adapted to extend through the said opening in the base and engage at the inner end with the fixed tubular suction member in the base and adjacent the outer end with the wall of the base, said hollow member having a longitudinal passageway leading from the exterior to the inner end of the hollow member and having a lateral passageway leading from an orifice through the wall of the hollow member in a region within the pressure chamber in the base, a jet tube located in said fixed tubular member, and a nozzle carried by said hollow member discharging into the jet tube, said nozzle at its receiving end being in communication with the lateral passageway through the wall of the hollow member.

7. In a pump, the combination of a hollow base and a surmounting casing providing two connected pressure chambers, one in the casing and one in the base, an opening from the exterior into the base pressure chamber, an impeller within the casing having its suction orifice by means of a passageway through the partition wall between the base and the casing, a fixed tubular member within the hollow base communicating at one end with the suction orifice of the impeller and at the other end having an open orifice within the base pressure chamber and registering with but spaced from said opening from the exterior into the base, and a hollow member adapted to extend through the said opening in the base and engage at the inner end with the fixed tubular suction member in the base and adjacent the outer end with the wall of the base, said hollow member having a longitudinal passageway leading from the exterior to the inner end of the hollow member and having a lateral passageway leading from an orifice through the wall of the hollow member in a region within the pressure chamber in the base, said hollow member having within it a passageway leading from the inner end of said lateral passageway to an orifice on the outside of the wall of the base, a pressure pipe in communication with the last mentioned orifice, and a jet pump coupled with said pressure pipe.
